FURNITURE SETTING DEVICE

Harold Pereira, Chicago, Ill., assignor to Kroehler
Mfg. Co., Naperville, Ill., a corporation of Illinois

Application September 25, 1939, Serial No. 296,409

1 Claim. (Cl. 35—53)

This invention relates to an improved furniture setting and consists of the matters herein-after described and more particularly pointed out in the appended claims.

5 A perplexing problem confronting every furniture dealer is how to display living room furniture to the best possible advantage. When two or three piece suites are viewed on a floor where they are surrounded in close relation by other suites, it is very difficult for a prospective purchaser to get a real picture of how the ones on view will appear when assembled in the room for which they are designed.

10 Some merchants have attempted to solve the problem by model rooms in which the suites are displayed. But these have proved unsatisfactory, first, because they are costly; a second, because they take up too much space; third, they are usually located in out-of-the-way places; 15 and fourth, many cannot be seen unless entered.

20 The object of the present invention is to provide a furniture setting in which suites of furniture may be exhibited as in a room in association with rugs and other furniture, so that the prospective purchaser may get an exact picture 25 of how the suite will appear when assembled in his own room in association with other furniture apt to be found there.

Another object of the invention is to provide 30 a furniture setting of the kind comprised of unit pieces which are capable of ready and easy assembly in any place where the setting is to be installed.

35 Another object of the invention is to provide a furniture setting of the kind which is of simple and economical construction, which occupies comparatively little space and in which the pieces of the suite of furniture displayed therein may be viewed at any angle.

40 These and other advantages of the invention will appear more fully in the following specification.

In the drawings:

45 Figure 1 is a perspective view of the improved furniture setting with a suite of furniture on display therein shown in dotted lines.

Figure 2 is a perspective view of the furniture setting with the several units which comprise it appearing in expanded relation.

50 Figure 3 is a perspective view of the improved furniture setting similar to Figure 1 but on a smaller scale and with a different arrangement of the pieces of the suite on display.

55 Figures 4, 5, 6 and 7 are diagrammatic plan views on a still smaller scale illustrating various

ways in which several furniture settings may be assembled on a floor, each designed to display a different suite of furniture.

Referring now to that embodiment of the invention illustrated in the drawings: 10 indicates the furniture setting as a whole when assembled with its component parts secured together and ready to receive the suite of furniture which is to be displayed. It comprises a vertical side wall 11; a vertical end wall 12 extending at right angles thereto at one end; a wall part 13 extending at right angles to the first named wall 11 at its other end; and a wall part 14 having an opening 14a therein and extending substantially at right angles to the wall 12.

15 Preferably the setting is provided with a floor piece 15. Said floor piece presents the furniture pieces in a position somewhat elevated from the floor of the show room in which the setting is placed, and thus more definitely sets out the suite of furniture on display in a manner to segregate it from any other suites of furniture that may be in the main room. It, however, may be omitted if desired.

20 Through the wide opening between the end of the wall part 13 and of the narrow wall part 14 the furniture pieces may be viewed as disposed in relation to the side wall 11 and the end wall 12. And to further simulate the effect of an actual room with the furniture pieces disposed 25 therein, a Venetian blind 16 may be fixed to hang upon the wall 12, as shown in Figure 1. Again, a mantle piece 17 may be fixed to the wall in any desired position, depending upon the furniture pieces and their designed relation 30 thereto. In Figure 1 said mantle piece, for example, is shown fixed to the wall 11 near one end adjacent the wall 12, whereas in Figure 3 said mantle piece is shown fixed midway of the length of the side wall 11.

40 The setting may be assembled with the end wall 12 and with the wall part 14 at either end of the side wall 11, this by merely reversing the position of the walls 12 and 13 as shown in Figure 1. This will appear by comparing the setting 45 18 in Figure 4 with the setting 19, and the setting 20 with the setting 21 in said view. This makes it possible to dispose the settings in various ways, depending upon the space at hand in the main room where the display is to be made.

50 In Figure 4, four settings 18, 19, 20 and 21 are disposed in the form of a rectangle, with their end walls 12 defining the shorter ends of the rectangle; the side walls 11 defining the longer sides of the rectangle; and with the wall parts 13 of 55

- the two pairs of settings placed over against each other and spaced apart. The two pairs of settings 18 and 19 on the one hand, and 20 and 21 on the other hand, are spaced apart to provide 5 an aisle or lane 22 between them through which customers may pass and from which they may view at any angle the furniture pieces disposed in said settings. In this array, the first view had upon entering the lane 22 will be through the 10 opening 14^a in the narrow wall part 14. As they pass on towards the wall section 13 of either setting they appear to actually enter into the room to a position where they will have a wide view of the furniture on display, and more particularly 15 its association with the side and end walls 11 and 12. This presents a close approximation to the actual appearance of the furniture pieces as they will appear when assembled in the room they are desired for furnishing.
- 20 In Figures 5, 6 and 7 are illustrated other ways of arranging the several settings. These are clear from the drawings and need no description. Other arrangements may be made, depending upon the space at hand and its relative dimensions.
- 25 The floor piece 15 may be covered by a rug of color or design to harmonize with the particular furniture on display in the furniture setting. And if the floor piece 15 be omitted, said rug or 30 carpet may be laid on the floor of the room in which the setting is disposed. Preferably the floor piece 15 has a curved edge 15^a running approximately parallel to a diagonal line between the remote corners of the room. This permits 35 a customer to approach so near the middle of the setting that he may actually view three corners of the room which the setting is designed to simulate.
- 40 The setting is made up of sections which are adapted to be readily assembled and secured together. Said sections are substantially identical

in construction. Four such sections 25 form the side wall 11, and three sections are included in the end wall 12. A section 25 and a half section 25^a comprise the wall part 13.

Each section 25 consists of an open frame 26 5 of any familiar construction covered with a light fibrous board 27 of any suitable material. A baseboard 28 is secured to each of the sections at the bottom, and a ceiling board 29 projecting forwardly from the fibre board 27 is fixed to 10 the top of the frame in each case.

The narrow wall part 14 has a base 30 from which rises an upright side member 31 and a rounded rod or bar 32 spaced therefrom. A ceiling board 29^a fixed to the tops of the side 15 member 31 and the rod 32 closes the opening 14^a at the top.

The upright side members of the several frames of the sections when said sections are in assembled relation are readily secured together in 20 any convenient manner but preferably by means of bolts and thumb nuts 33 which take through suitable openings 34. This permits of the ready assembly of a furniture setting. When it is to be removed to another place, it is readily dis- 25 assembled for convenience in transporting.

I claim as my invention:

A furniture setting device comprising a vertical side and a vertical end wall, a narrow vertical wall part extending at right angles to said side 30 wall at one end thereof, and a narrow vertical wall part with an opening therein extending at right angles to said end wall and parallel to said side wall at the opposite end thereof, said two narrow wall parts being relatively proportioned 35 in width to present a wide opening between them in a line extending approximately parallel to the diagonal line connecting the ends of said side and end walls remote from each other.

HAROLD PEREIRA.
